UNITED STATES PATENT OFFICE.

WILLIAM C. BURRELL, OF KANKAKEE, ILLINOIS, AND JOHN BELLINGHAM, OF MASTERTON, NEW ZEALAND, ASSIGNEES TO SAID BELLINGHAM AND WILLIAM BOYCE CHENNELLS, OF MASTERTON, NEW ZEALAND.

BLOCK-PRESS.

1,374,818.

Specification of Letters Patent. Patented Apr. 12, 1921.

Application filed December 14, 1917. Serial No. 207,070.

To all whom it may concern:

Be it known that we, WILLIAM C. BURRELL, a citizen of the United States of America, and residing at 622 Greenwood 5 avenue in the city of Kankakee, in the county of Kankakee, State of Illinois, and JOHN BELLINGHAM, a citizen of the Dominion of New Zealand, whose permanent address is Masterton, in the provincial District of Wellington, in the Dominion of 10 New Zealand, and temporarily resident at 4312 Kenmore avenue, Chicago, Illinois, have invented certain new and useful Improvements in Block-Presses, of which the 15 following is a specification.

Our invention relates to block presses and has for its primary object the provision of an improved block press which shall have improved means whereby the pressed article 20 may be removed from the press in perfect condition. Other objects of our invention are:

To provide, in combination with a downwardly discharging mold, a table and means 25 whereby the table supports the article during the process of molding the same, descends vertically from the mold and, following said descent, glides laterally in the press to bring the finished article sufficiently clear 30 of the main frame of the machine to facilitate its removal; to provide rigid anti-friction elements for lateral movement of the table in the press and resilient members supporting a table in spaced relation to the 35 elements whereby, upon compression of the members, the table top contacts with the rigid anti-friction elements and gives a rigid support opposing pressure exerted upon the mold; to provide a mounting and guides for 40 said table whereby lateral movement of the table is prevented until it has descended from the mold a distance slightly greater than that from the bottom of the mold to the top of the mold cavity; to so construct 45 said table mounting that the table may be operated independently of other parts of the press; to so construct said table and its mounting that it opposes pressure exerted upon the mold; to provide an improved form 50 of pressing device; to provide a mold movable laterally in a raceway, a pressing device having a normal tendency to enter the path of movement of the mold, a table frame

lowered by gravity and a connection between the pressing device and the table 55 frame whereby the device is normally held out of the path of movement of the mold; to provide a pressing device bodily adjustable with respect to the pressing position of the mold; to provide a pressing device, toggles 60 for operating the same, actuating means for the toggles; a support for the toggles adjustable with respect to the mold and an actuating element for the toggles independently adjustable with respect to the mold and 65 the toggle supports; to provide an improved form of mold which, while constructed for downward discharge of a molded article, is invertible and movable laterally of the pressing device to facilitate charging; to 70 provide an improved form of expanding mold the walls of which, in expanded position, diverge downwardly from the molded article; to provide expanding wall molds 75 in combination with cores movable laterally of said walls; to provide an improved construction for simultaneous operation of such a wall and core; to provide an improved mold construction whereby the finished article is given a deep peripheral recess and a relatively shallow peripheral channel opening angularly into said recess; to provide an improved form of mold 80 plunger constructed to resist distortion under great pressure; to provide an improved 85 plunger and means for adjustably limiting its movement in the mold whereby the depth of the mold cavity may be varied; to provide a mold centrally trunnioned on a horizontal axis and shaped to form an article which is 90 heavier on one side of said axis than the other, in combination with a constantly horizontal movable table arranged to prevent tilting of the mold and to support in and carry from the mold such an over- 95 balanced article.

Other objects and advantages of our invention will appear from the following description together with the accompanying drawings which form a part of this specification and illustrate the preferred embodiment of the invention.

In the drawings:

Figure 1 is a side elevation of the invention;

Fig. 2 is the rear end elevation thereof

with parts broken away and illustrating that position of the parts wherein an article is being pressed within the mold;

5 Fig. 3 is a section taken approximately on line 3—3 of Fig. 2.

Fig. 4 is a fragmentary section taken on line 4—4 of Fig. 3;

10 Fig. 5 is a side elevation of the mold forming a part of our invention and illustrating in section, portions of a carriage and a trunnion by means of which the mold is supported in carriage;

15 Fig. 6 is a mutilated section taken approximately on line 6—6 of Fig. 5, looking in the direction indicated by the arrows;

20 Fig. 7 is a section similar to Fig. 6 showing the discharging position of the mold parts and including on opposite sides of the mold the outer ends of bearing rods by means of which a core bar is supported in the mold frame; these bearing rods in Fig. 5 stand slightly to the right of the section line 6—6, but are inserted in Fig. 7 for better understanding of the invention;

25 Fig. 8 is a plan view of the mold and its carriage, certain pillow blocks normally attached to the mold plunger being omitted for the sake of clearness;

30 Fig. 9 is a horizontal fragmentary mutilated section taken substantially on line 9—9 of Fig. 5;

35 Fig. 10 is an end elevation of a modified form of plunger for the mold which is adapted to form a molded article heavier at one end than the other;

40 Fig. 11 is a section on line 11—11 of Fig. 10, looking in the direction indicated by the arrows and including portions of the mold box together with an article being formed therein;

Fig. 12 is a fragmentary section taken on line 12—12 of Fig. 11.

Reference numeral 20 indicates generally a base comprising broad parallel channels 21 and 22 spanned by the heavy steel plate 23 riveted on its edges to the tops of the channels. This base is of sufficient width to accommodate the movement of various parts hereafter to be described, and from opposite sides of the base rise parallel pillars numbered 24 and 25 on one side of the press and 26 and 27 respectively on the opposite side. Near their upper ends the pairs of pillars 24 and 25, and 26 and 27, are respectively joined by cross bars 28 and 29. Preferably the pillars 24 to 28 are channel shaped in cross section with their concavities opening toward each other to accommodate between their side webs vertical tension rods 31 and 32 on one side of the machine and 33 and 34 on the opposite side, these tension rods being bolted by nuts 35 to the base channels 21 and 22, and at their upper ends secured to horizontal brackets 36 formed at the upper ends of the pillars, nuts 37 being

threaded on the tension rods above said brackets. The pillars and tension rods, together with their cross bars 28 and the base 20, form the main frame of our invention.

Rising from the base 20 are posts 38 and 39 on one side of the press and 41 and 42 on the opposite side, the posts 38 and 41 being

opposite each other and 39 and 42 being also opposed on the opposite sides of the base and spaced from the posts 38 and 41.

Mounted in suitable bearings formed near the base of the main frame are three parallel horizontally aligned shafts 43, 44 and 45, each supporting the lower end of one of three table legs 46, 47 and 48 which move in

parallelism and at their upper ends are pivoted on axles 49, 51 and 52, respectively, to a table frame generally indicated at 53 and comprising spaced parallel rails 54 and 55.

The leg 47 is fixedly mounted on shaft 44, 85

the latter carrying a fixed table frame operating arm 56 and preferably a similar shorter arm 57 for convenience in manipulation.

By manipulation of arm 56 or 57 the table frame 53 is elevated from its lower

position shown in Fig. 1, to its upper position illustrated in Figs. 2 and 3; the position of arms 56 and 57 in the upper position

of the table being indicated by the dotted center lines 58 and 59 respectively in

95 Fig. 1. Rising from the bearings 61 and 62 of shaft 43 are a pair of spaced studs 63 and 64 which uphold, respectively, compression springs 65 and 66 adapted to extend

above the studs and to receive and cushion the fall of the table frame 53.

In the elevation of the table frame the legs 46, 47 and 48 move from their slanted position in Fig.

1 upwardly through the vertical and slightly past it to the position shown in Fig. 3, and

when they have completed this movement, a

detent 67 secured laterally of the table frame strikes the pillar 26 laterally preventing on-

ward movement of the table legs. By this construction the table frame is maintained

110 in elevated position against vertical pressure exerted against it.

The movement of the table frame 53, consider-

115 ing its position in Fig. 3, is rearwardly of the main frame to the position shown in Fig. 1; it being applicants' intention

throughout this specification to consider the left hand end of the press as viewed in

Fig. 1 as the forward end, and the right hand end, the rear end. Horizontally fixed

120 upon the upper ends of the posts 38, 39,

41 and 42 are parallel rails 67 and 68 forming

125 a raceway for travel of the mold generally indicated at 69 in Figs. 1, 2 and 3.

As best seen in Figs. 1 and 3, the mold is

128 adapted to enter a position centrally of the

pillars of the main frame and discharges

130 downwardly from that position. At opposite ends the rails 67 and 68 are provided with bumpers 71 whereby travel of the mold

in its raceway is limited. Positioned for travel upon the table frame is a table best shown in Figs. 3 and 4 comprising the top 72 provided at its side edges with longitudinally disposed angle irons 73 the webs 74 of which are vertically slotted as at 75 to provide bearings for a plurality of axles 76 which carry, preferably integral therewith, rigid metal rollers 77, these rollers 10 running upon the rails 67 and 68. The top 72 and angles 73 are held spaced above the rollers 77 by leaf springs 78 which extend longitudinally of the table, are riveted thereto at their centers and down bent from 15 the table top, the ends of these springs bearing upon the tops of the axles 76. Normally the springs 78 maintain the table top 72, the angles 73 and the rollers 77 in the position illustrated in Fig. 4 wherein there 20 is a space between the bottoms of the horizontal webs of the angles 73 and the tops of rollers 77. In this position of the parts the table 72 glides upon the table frame. Projecting laterally from the sides of the table 25 and centrally thereof are a pair of guide studs 79 preferably journaled upon stub shafts 81 to reduce friction of the studs. When the table is at the rear end of the lowered table frame as in Fig. 1, it is easily 30 moved by hand inwardly of the press to the vertical center thereof. Fixed to each of the posts 38 and 41 is a pair of vertically positioned channel guides 82 and 83, the lower end of the forward guide 82 depending 35 substantially the thickness of one of the studs 79 below the level of the lower end of the rearward guide 83, the lower ends of guides 82 standing level with the studs 79 to limit inward travel of the table 40 upon the table frame. With the parts as illustrated in Fig. 1 the table is moved by hand until studs 79 strike guides 82 following which the elevation of the table frame causes the frame to glide under the table 45 and to elevate the table in constantly horizontal position and in a vertical path until detent 67 strikes pillar 26, when a spacing plate 84 carried upon the table top 72 strikes a palette board 85 forming a movable bottom for the mold 69. As the table frame is 50 elevated the table and its rollers 77 maintain the spaced relation shown in Fig. 4 until the frame has almost reached its highest point. Just before this point is reached 55 the spacing plate 84 strikes the palette board 85 and the completion of the elevating movement of the table frame compresses springs 78, because of the weight of the mold, bringing the horizontal webs of angles 73 of the 60 table into direct contact with the rigid rollers 77 thus providing a rigid support from the base of the machine to the palette board 85 for resisting downward pressure upon the mold. The springs 78 are, however, of 65 sufficient strength to elevate the table above

the rollers when the table frame is lowered, even under the weight of a block freshly molded and discharged upon the table. As the table frame descends the studs 79 traverse the vertical guides 82 and 83 until the 70 table frame is at the bottom of its path of movement. In this position the studs 79 are clear of the guides 83 and the table is easily rolled by hand to the rear end of the table frame where the finished article stands 75 clear of the main frame of the machine and is thus conveniently accessible for removal. As best seen in Fig. 4 the bearings 74 of the table overlap the outer surfaces of the table frame rails 67 and 68 thereby preventing 80 displacement of the table laterally of its frame.

The pressing device of our invention comprises a presser foot 86 strengthened by trusses 87 formed on its upper surface in 85 combination with toggle mechanism and means for actuating the same. For a considerable distance the upper ends of the tension rods 31, 32, 33 and 34 are threaded, and embracing the upper ends of these rods 90 are a pair of parallel yokes 88 and 89, yoke 88 at its opposite ends embracing and traveling upon tension rods 31 and 33 and yoke 89 similarly engaging rods 32 and 34. Above and below the ends of each yoke are 95 lock nuts 91 threaded upon the tension rods to maintain the yokes in any given elevation. Each pillar of the main frame is provided somewhat below the normal position of the yokes 88 and 89 with an oblique 100 brace 92 pivotally bolted at its lower end 93 to the pillar and longitudinally slotted at its upper end for engagement by a bolt 94 which passes through the slot and is fixed in the adjacent yoke at a point remote 105 from the tension rod. Thus the main frame of the machine on each side of the press is spanned by yokes 88 and 89 and the press strengthened against weaving by braces 92. It is to be noted that the construction just 110 described provides a considerable amplitude of vertical adjustment for yokes 88 and 89 while retaining at all times the necessary rigidity in the frame of the press. From each of the yokes 88 and 89 is pivotally suspended a set of toggles 95 knuckled at their meeting ends on a horizontal shaft 96 and pivotally connected at their lower ends on shaft 97 to the trusses 87 of presser foot 86, the presser foot being constantly maintained in horizontal position. At each side of the main frame a pair of spaced hangers 98 are suspended for vertical adjustment from cross bar 28. Suspended from each pair of hangers 98 is a bridge 99 fitting 115 between the pillars 24 and 25 or 26 and 27, as the case may be, and having extended ends 101 which overlap the inner and outer sides of each pillar. The bridges 99 are apertured for passage of the hangers 98 and 120 125 130

the threaded lower ends of the hangers carry nuts 102 above and below the horizontal web of the bridge, this construction providing for vertical adjustment of the bridges 5 independently of yokes 88 and 89. Mounted on each bridge is a shaft bearing 103, these bearings being coaxial and adapted to rotatably support a horizontal main shaft 104 carrying fixed opposite link arms 105. 10 Links 106 connect the arms 105 to the knuckle shafts 96 of the respective sets of toggles whereby rotation of main shaft 104 causes actuation of the toggles. As best seen in Figs. 1 and 2, the shaft 104 carries 15 fixed operating arms 107 and 108. Considering the parts in the position of Fig. 1, downward movement of operating arm 107 to a position indicated by the dotted center line 109 will rotate the main shaft 104 and 20 straighten the opposite sets of toggles 95 into the position illustrated in Figs. 2 and 3, thus lowering presser foot 86 and causing it to exert pressure downward in a vertical direction upon the mold. 25 It will be obvious from Fig. 1 that the weight of the presser foot 86, the toggle sets 95 and the operating arms 107 and 108, which are substantially parallel, gives the pressing device as a whole a tendency to 30 lower the presser foot 86 into the path of movement of mold 69 due to the force of gravity upon those parts. A drag arm 111 is fixed upon the main shaft 104 and at its 35 tip carries the upper end of a chain 112 connected at its lower end to a reach bar 113 projecting laterally from the table frame 53. The drag arm 111 projects from shaft 104 in a direction diametrically opposite to operating arms 107 and 108 and, as the 40 table frame is sufficiently heavy, it counterbalances the normal tendency of the pressing device to descend into the path of movement of the mold. Consequently, it is seen that in initial elevation of the main frame 45 and table frame—the mold being already centrally positioned in the main frame as in Fig. 3—the chain 112 causes the weight of the pressing device parts to partially offset the greater weight of the table thus 50 considerably lessening the labor of the operator. Preferably a turn buckle 114 is inserted in chain 112 for the purpose of adjustment. For convenience in operation the arms 107 and 108 are positioned as shown with respect to shaft 104, it being plain from Figs. 55 1, 2 and 3 that when the greatest pressure is being exerted by presser foot 86 the operating arms are near the ground where they are readily grasped and moved by the 60 operator.

Each of the rails 67 and 68 of the mold raceway carries a pair of rollers 115 and on these rollers is supported a mold carriage 116. A mold frame 117 is provided centrally with co-axial laterally extending

trunnions 118 journaled in the carriage 116. Thus the mold frame is mounted for inversion in the carriage and for horizontal travel in the raceway. In referring to the mold those parts will be considered as top and 70 bottom which are respectively uppermost and lowermost when the mold is positioned below presser foot 86 and in a condition to receive pressure. It is to be understood, however, that for convenience in filling and 75 discharge the mold is invertible, the bottom being uppermost in Fig. 1 where the mold stands at the forward end of its raceway in position to be charged with concrete. Mounted in the upper portion of the mold 80 and spaced somewhat within its sides and ends are four horizontal rectangularly disposed pivot rods 119 (see Figs. 6, 7 and 8) upon which are mounted out-turned lugs 121 formed at the upper extremities of opposite side walls 122 and opposite end walls 123, these four walls forming a mold box. At their lower ends side walls 122 are formed with outturned horizontal flanges 124 and similar flanges 125 are formed on 90 the lower edges of end walls 123. As best seen in Figs. 6 and 9, expansion springs 126, adjustably mounted in the mold box frame 117 are connected in pairs to each side and end wall near its vertical edges to give said 95 walls a normal bias toward expansion from the closed position of the mold in Fig. 6 to its opened position shown in Fig. 7. We prefer a construction wherein a chamber 126^a is formed in the mold frame 117 and 100 apertured at its inner end for passage of a spring post 126^b secured at its inner end into the side or end wall and carrying at its outer end an adjustable nut 126^c between which and the inner face of chamber 126^a 105 the spring 126 is compressed. Referring to Fig. 9 it will be seen that the end walls are closed by means of a rotatable collar 127 mounted in a post 128 bottomed in flange 125 and carrying, in addition to a handle 129, a projection 131 adapted to be moved in an arcuate path to and against the mold frame 117 and limited in such movement by a stop 132 set in the frame. The projections 131 are so disposed as to force their 110 respective end walls inward of the mold to closed position against the force of springs 126 and to hold the end walls closed against pressure exerted in the mold, the axes of these projections standing perpendicular to the frame 117 in the closed position of the end walls and in alignment with the center of post 128. Such a position of the parts is 115 illustrated in Fig. 9, and by counter-clockwise movement of handle 129, as seen in that figure, the end wall 123 may be released for movement to expanded position under the influence of springs 126. Viewing Figs. 6, 7 and 9 it will be seen that on 120 each side of the mold frame a horizontal 125

130

mold operating shaft 133 is journaled at its ends in bearings 130 formed in the ends of the mold box frame. These shafts stand between the side walls 122 and the mold frame. Means for turning the shafts 133 are provided at each side of the machine in a shaft operating lever 134 pivoted on one of the trunnions 118 and universally pivoted (see Fig. 6) by means of a ball and socket joint 135 to a shaft operating arm 136 extending tangentially from shaft 133 and bent at right angles for pivotal mounting radially in the shaft. Inasmuch as the ball and socket joint 135 moves in an arcuate path, the pivotal mounting of operating arm 136 provides sufficient play in that portion of the arm which is tangential to the shaft to accommodate the arcuate movement. Each of the side walls 122 is provided on its outer face, opposite shaft 133, with a cam 137 having a lower face standing oblique to the outer surface of the wall and an upper face paralleling said surface. Mounted in shaft 133 is a pin 138 carrying a cam finger 139 positioned to ride upon said surfaces and to close the side walls against the pressure of their springs 126; each cam finger in the closed position of the side walls, abutting that surface of the cam lying parallel to the plane of the side wall and having its axis perpendicular to the wall and in alignment with the axis of shaft 133. By this construction the side walls are closed against the force of springs 126 and held closed against pressure from within the mold. The mold shaft operating levers 134 preferably extend to the same end of the mold frame for convenience in operation. By movement of these levers from the position illustrated in Fig. 5 to the position indicated by dotted center line 141 in that figure, each side wall is released to expansion under the influence of springs 126, the walls then assuming the position shown in Fig. 7.

Referring to Figs. 5, 6, 7 and 9 it will be seen that, spaced slightly from their lower edges the side walls are transversely apertured as at 142 for sliding movement through the apertures of cores 143 carried on a horizontally disposed core bar 144 which parallels the outer surface of the side wall on each side of the mold and carries a pair of outwardly projecting bearing rods 145 loosely mounted for sliding movement in slots 146 in the frame. These core bars and cores are actuated from levers 134 through the medium of arms 147 mounted by means of collars 148 on operating shafts 133. Each core bar carries a pair of spaced outwardly extending lugs 149 in each of which is pivoted a wrist block 151 diametrically apertured at right angles to its pivotal axis for engagement by core bar operating arm 147.

65 The arm 147, being centered at one end of

shaft 133 is by the construction just described mounted for sliding movement in wrist block 151 and by reason of the fact that the mold operating shafts 133 are considerably above the core bars 144, the resulting length of arm 147 provides for movement of the cores through a path considerably longer than the path of movement provided for adjacent portions of the side walls 122. The side mold operating mechanism therefore moves the side walls to closed position from the relation of parts shown in Fig. 7 to that of Fig. 6 and simultaneously shoots the cores 143 into the mold cavity until core bars 144 strike the side walls. 70 Upon reverse movement of the cores the walls are expanded from each other to permit descent of a finished block from the mold and the sliding cores 143 are withdrawn preferably outwardly of the inner 75 surfaces of the side walls 122 as illustrated in Fig. 7. The sliding cores 143 on the inner side and the bearing rods 145 on the outer side properly support the relatively heavy core bars 144. Obviously, sliding cores of 80 any desired number and shape may be mounted on the core bar for movement through the side walls. For the purpose of forming peripheral grooves 152 in the finished block half round bars of steel 153 may 85 be removably secured in any suitable manner not shown to the inner faces of side walls 122.

The mold plunger which we employ is generally indicated at 154 in Figs. 3, 6 and 100 7 and comprises a substantially horizontal molding wall 155 provided with one or more transverse upstanding corrugations 156 carrying down-turned projections 157, the corrugations and their projections being employed to form reinforced spacing studs 158 on the back of the finished block as best seen in Figs. 3 and 6. The plunger 154 is movable vertically between the side and end walls of the mold box and is adapted to 105 receive the thrust of presser foot 86 upon thrust webs 159 which rise vertically from the apices of corrugations 156 thereby providing an extremely strong plunger reinforced against distortion under pressure by 110 reason of the fact that thrust webs 159 are bottomed in the arched corrugations, these corrugations being immediately strengthened by means of the downward projections 157. Somewhat above its middle each side 115 of the plunger 154 is provided with vertically disposed spaced slots 161 standing opposite each other in pairs and engaged by a pair of distance rods 162 (see Figs. 3, 5, 6 and 7) which are loosely mounted in bearing apertures 163 formed in the upper portions of the side walls 122. The slots 161 extend upwardly to any suitable distance in order that the plunger may descend so far 120 in the mold box as to form a mold cavity of 130

any desired minimum thickness. As to downward extension the plunger slots 161 are of a length sufficient to permit their elevation in the plunger as far as necessary to provide a mold cavity of any desired maximum depth. As a matter of fact, the plunger in moving from the compressed position illustrated in Fig. 6, wherein the mold cavity is occupied by a finished block 164, to a position farther removed from the position of the palette board 85, actually drops in the mold box because of inversion of the mold in the carriage 116. The slots 161 provide for a maximum drop of this kind but this retracting movement of the plunger from the lower ends of the side and end walls is limited by means of a stop bar 165 spanning the tops of the thrust webs 159 (see Figs. 3, 6 and 8) and engaged, through apertures provided, by a pair of eye bolts 166 each of which embraces at its lower end the center of one of the thrust rods 162 and carries a stop nut 167 threaded at its upper end. When the mold is inverted the thrust webs, in dropping with the plunger, carry stop bar 165 downwardly with them until the stop bar strikes the stop nuts 167. By adjustment of nuts 167 on eye bolts 166 the depth of the mold cavity to be charged with concrete is varied it being understood that in the operation of the present invention the mold cavity, when charged, must normally be of greater depth than the thickness of the finished article in order to provide for the compression which results from the action of the pressing device. When the mold is in its upright position in the center of the press as illustrated in Figs. 2, 3, 5, 6 and 7 the downward travel of the plunger is preferably limited by the concrete being pressed rather than by contact between any relatively movable parts of the mold. Thus it will be seen in Fig. 6 that the upper ends of slots 161 stand above the top of stop rod 162 even though the article 164 is under full compression. Preferably we provide parallel spaced pillow blocks 168 paralleling stop bar 165 and removably secured by bolts 169 across the upper edges of the thrust webs 159. These blocks are preferably made of wood and stand slightly above the upper edges of the walls of the plunger, the presser foot 86 being shaped to descend between the side and end walls of the mold box and upon the tops of the pillow blocks 168.

Referring to Figs. 6, 7 and 9 it will be seen that in the outer surface of each side wall in plunger 154 a vertically disposed channel 171 is cut which extends from substantially the center of the side walls of the plunger downwardly and intersects the molding face 172 thereof. Positioned on the inner face of each side wall is a fixed core 173 shaped to closely fit and slide in the channels 171, these fixed cores 173 extending

downwardly below the normal lower position of the molding face 172 of the plunger and having their lower extremities flush with the upper portions of the core apertures 142, the lower extremities of the fixed cores being shaped to conform to the configuration of the core apertures 142 in order that cores 173 may slide in contact with the lower extremities of the fixed cores. Inasmuch as cores 173 are shot into the mold cavity a distance greater than the horizontal thickness of the fixed cores 173 the result of the action of the mold in this respect is the formation in the finished article of a deep recess 174 and opening rectangularly from the same a shallower groove 175 which intersects the back or upper surface of the finished article as that article is viewed in Figs. 6 and 7. By this coring construction the finished block is cored in a manner which greatly facilitates its use. The fixed cores 173 and their channels 171 in the plunger not only extend parallel with the direction of movement of the plunger in the mold box but are likewise of sufficient extent to permit the making of a block of maximum thickness without disengagement of the fixed cores from their channels so that, when the mold is inverted for charging as in Fig. 1, the plunger may be retracted to the capacity of the mold without uncovering the channels 171 thereby preventing the entrance of concrete into these channels during the inverted closed position of the mold.

When the freshly molded block 164 has been discharged from the mold it rests upon the palette board 85 which itself lies upon the spacing plate 84 positioned on the table top 72. The mold is subsequently closed from the position of Fig. 7, to the position shown in Figs. 3, 5, 6, 8 and 9, and is then inverted and drawn along its raceway to the charging position as illustrated in Fig. 1. Concrete is now poured into the upwardly exposed open mold cavity in quantity necessary to form another block. Bolted to each flange 125 of the end walls 123 of the mold box is a plate 176, spaced the thickness of the palette board 85 from the flange by means of a spacing block 177 which has its inner edge disposed outwardly of the inner edge of the plate in each instance, forming a palette board support which embraces the ends of the palette board and overlies its outer surface. When the inverted mold has been charged with concrete the palette board 85 is slidably inserted between the spacing blocks 177 to close the mold cavity, the flanges 125, the spacing blocks 177 and the plates 176 embracing respectively the inner surface, the end edges and the outer surface of the palette board preventing dislodgment of the palette board from the mold upon reversing the latter from the charging position to the pressing

- position shown in Figs. 3, 6 and 7. When the end walls of the mold are released by operation of the handles 129 the end walls expand from each other under the influence 5 of their springs 126. The separation of the lower ends of the end walls 123 is ample to draw plates 176 outwardly beyond the ends of the palette board 85 thus releasing the board for transportation upon the table.
- 10 The spacing plate 84 is provided upon the table in order that the palette board plates 176 shall clear the top of the table during the opening movement of the mold.
- In Figs. 10, 11 and 12 is illustrated a 15 modified form of plunger for the mold box of our invention shaped to form a block much heavier at one side of the mold trunnion axis 118 than at the other, this block, numbered 178, being a corner block for use 20 in connecting angled walls. Were it not for the constantly horizontal position of the table and the construction whereby the table is in contact with the palette board when the molded block is released, the overbalanced 25 condition of the block 178 would cause the mold to tilt to the heavier side on its trunnions and drop the block, or the one end of it upon the table with the shattering of the block as a probable result. This modified 30 form of plunger is indicated at 179 and, in Figs. 11 and 12, it is shown as positioned in the end walls of the mold box and above the palette board 85. By reason of a core 181 provided in the angle between the horizontal 35 and substantially vertical molding surfaces 182 and 183 respectively of the plunger 179 the block 178 is formed with two edge gussets 184 which serve to strengthen the union between the angularly extending portions of 40 the block. It is obvious that the configuration of the molding face of the plunger of our invention may be altered in various ways but by the positioning of table 72 the mold, though overbalanced at one end on its 45 trunnions 118, will always discharge its block in horizontal position upon the table without jar or lateral sliding of the block on the table.
- In the operation of our invention and 50 considering the members initially in the positions shown in Fig. 1, the table is rolled inwardly until studs 79 strike guides 82. The press is designed to be most conveniently operated by two workmen. One of these 55 men charges the inverted open mold cavity with concrete and slides palette board 85 into position, as in Fig. 1, following which he reverses the mold in its trunnion and pushes it into the position shown in Fig. 3. The 60 same workman now pulls operating arm 108 downwardly to assist the other workman who is pulling upwardly on arm 56 to bring the table frame to elevated position. When the 65 table frame has nearly approached elevated position spacing plate 84 strikes the bottom of palette board 85 compressing the springs 78 and bringing the table into direct contact with the rigid rollers 77, the chain 112 transferring part of the force exerted upon arm 108 to the table frame during the greater 70 part of the upward movement of the table frame. Just before exerting the greatest force upon the main shaft 104 the operator pulling on arm 108 allows that arm to stand stationary while the other operator, by 75 means of arm 57, completes the elevation of the table and until legs 46, 47 and 48 have passed through the vertical portion and detent 67 has struck against pillar 26. Both operators now respectively grasp the arms 108 80 and 107 and pull those arms to the position indicated by the dotted center line 109 of Fig. 1 and by the full line positions in Figs. 2 and 3. The force which they now exert upon shaft 104 drives plunger 154, or 179, 85 as the case may be, against the concrete charge compressing the same into block 164 or 178. The block is now formed and ready to be discharged. The operators rotate both handles 129 and the operating levers 134 of 90 the mold, the handles 129 expanding the end walls 123 of the mold and the levers 134 expanding the side walls of the mold and simultaneously withdrawing cores 143, not only with respect to the cored article, but 95 also with respect to the molds themselves. The walls of the mold are now in the position illustrated in Fig. 7. The operators now move arms 108, 107, 56 and 57, withdrawing presser foot 86 from contact with the pillow blocks 168 and lowering the table frame to the position it occupies in Fig. 1. The descent of the molded article permits the plunger 154 to drop to the limit allowed 100 by the slots 161 following which, the completed block 164 travels in a horizontal position vertically downward from the mold until the table frame is fully lowered, following which, one of the operators draws the table to the position shown in Fig. 1, when 105 he removes the freshly molded article from the table, the article still standing upon the palette board 85 on which it was molded. Handles 129 are now operated to close the end walls 123 of the mold box and the mold 110 operating levers 134 are also oppositely rotated upon trunnions 118 to close side walls 123 and simultaneously shoot cores 143 into the position shown in Fig. 6. The mold is now run in carriage 116 along the raceway 115 rails 67 and 68 to the outer end of the raceway where it is inverted to the position shown in Fig. 1. Upon this inversion of the mold the plunger 154 drops within the closed mold box until stop bar 165 strikes stop nut 120 167: by this means the plunger is retracted in the mold to form a mold cavity which will hold an amount of concrete that will, when compressed, form a block of desired 125 thickness. When stop bar 165 strikes stop 130

nut 167 in the last above mentioned position of the mold, the press is ready for recharging and repetition of the operations just described.

5. We claim:

1. In a block press, the combination with a downwardly discharging mold, of a table frame mounted in the press for movement in a constantly horizontal position toward and 10 from the bottom of the mold through an arcuate path, a table glidingly mounted on said table frame, and vertical guides fixed in the press and engaged by the table whereby the table is reciprocated vertically during 15 the movement of the table frame.

2. In a block press, the combination with a main frame, of a table frame mounted in the main frame for movement in a constantly horizontal position through an arcuate path, a table glidingly mounted on said 20 table frame, and vertical guides fixed on the main frame and engaged by the table whereby the table is reciprocated vertically during 25 the movement of the table frame.

3. In a block press, the combination with a main frame, of a table frame mounted in the main frame for movement in a constantly horizontal position through an arcuate path, a table glidingly mounted on the 30 table frame, guide studs projecting from the table, and channel shaped vertical guides fixed on the main frame for engagement by said studs whereby the table is vertically reciprocated during the movement of the table 35 frame; corresponding legs of said guides terminating short of the lower ends of the respectively opposed legs whereby, the table, when lowered, is permitted movement laterally on one side only of the guides.

4. In a block press, the combination with a main frame, of a table frame positioned therein; a mounting for the table frame comprising parallel spaced legs of equal 40 length pivoted at their upper ends on parallel axes in the table frame and at their lower ends on parallel axes in the main frame; a table glidingly mounted on the table frame, and vertical guides engaged by the table whereby the table is reciprocated vertically 45 during movement of the table frame.

5. In a block press, the combination with a main frame, of a table frame positioned therein; a mounting for the table frame comprising parallel spaced legs of equal 50 length pivoted at their upper ends on parallel axes in the table frame and at their lower ends on parallel axes in the main frame; a table glidingly mounted on the table frame, and vertical guides engaged by the table 55 whereby the table is reciprocated vertically during movement of the table frame, said table frame, when lowered, projecting from one side of said main frame, and the corresponding sides of said vertical guides being 60 shortened at their lower ends.

6. In a block press, the combination with a table frame, of a table, vertically slotted bearings depending from the table, rollers adapted to run on the table frame and journaled in said slots, and springs interposed 70 between the rollers and the table whereby the table is normally supported upon and spaced above the rollers, said table overlying the rollers and resting directly thereon when said springs are compressed. 75

7. In a block press, the combination with a table frame, of a table, vertically slotted bearings depending from the table, flat surfaced rollers adapted to run on the table frame and journaled in said slots, and 80 springs interposed between the rollers and the table whereby the table is normally supported upon and spaced above the rollers, said bearings overlapping the sides of the table frame to guide the table longitudinally 85 thereof, said table overlying the rollers and resting directly thereon when said springs are compressed.

8. In a block press, the combination with a table frame constituting a horizontal 90 track; of a table adapted to travel on the same and comprising a top, and vertically slotted side flanges depending from the top; rollers journaled in the slots of the flanges, and leaf springs supported from the rollers 95 and exerting upward pressure on the table top whereby said top is normally held spaced above the rollers, said table overlying the rollers and resting directly thereon when said springs are compressed. 100

9. In a block press, the combination with a table, a track therefor, of table carrying elements running on the track, and compressible means normally holding the table spaced from said elements, said means being 105 compressible to bring the table and said elements into contact.

10. In a block press, the combination with a table having depending flanges, and a track therefor, of axles journaled in vertical 110 slots formed in said flanges, leaf springs fixed to the table, the free ends of said springs being bent downwardly from the table and bottomed on said axles, and track supported rollers carried by the axles, said 115 springs being compressible to bring the table and said rollers into contact.

11. In a block press, the combination with a mold, of a table frame below the same, mechanism for raising and lowering said 120 frame, table carrying elements on the table frame, a table, and resilient means normally holding the table spaced above said elements; said mechanism being so proportioned that its complete elevation causes 125 contact between the table and mold and subsequent contact between the table and said elements.

12. In a block press, the combination with a main frame and a mold, of a table frame, 130

- mechanism whereby the same is mounted below the mold for movement in a path extending downwardly and outwardly thereof, table carrying elements running on the 5 table frame, a table, resilient means normally holding the table spaced above said elements, guide studs projecting from the table, and vertical guides engaged by said guide studs whereby the table is vertically reciprocated during the movement of the 10 table frame, said mechanism being so proportioned that its complete elevation causes contact between the table and mold and subsequent contact between the table and said 15 elements.
13. In a block press, the combination with a main frame, of a mold movable therein, a pressing foot having a gravity induced tendency to enter the path of movement of 20 the mold, a gravity lowered table carrying frame of sufficient weight to overcome said tendency, and connections whereby the foot is counterbalanced by said table frame.
14. In a block press, the combination of a 25 pressing foot urged by gravity toward its operative position, a table carrying frame lowered by gravity, and connections whereby said foot is drawn to its inoperative position by the descending table frame.
15. In a block press, the combination of a 30 movable mold, a pressing device having a gravity induced tendency to enter its operative position in the path of movement of the mold, a gravity lowered table frame adapted, when in its raised position, to oppose pressure exerted on the mold by said device and a connection between said device and the table frame whereby they counterbalance each other and whereby operation of 35 said device elevates the table frame.
16. In a block press, the combination with a main frame, and a laterally movable mold, of a pressing device mounted for vertical adjustment in the main frame and having a 40 gravity induced tendency to enter its operative position in the path of movement of the mold, a gravity lowered table frame adapted, when in its raised position, to oppose pressure exerted on the mold by said 45 device, and an adjustable connection between said device and the table frame whereby they counterbalance each other and whereby operation of said device elevates the table frame.
17. In a mold, the combination with a 50 mold frame; of a mold box comprising opposite walls pivoted in the frame; a plunger reciprocable between said walls and provided with oppositely registering slots 55 elongated in the direction of reciprocation, and a stop rod having its ends loosely mounted in said walls and traversing the slots of the plunger.
18. In a mold, the combination with a 60 mold frame; of a mold box comprising op-
- posite walls movably mounted in the frame; a plunger reciprocable between said walls, and means carried by the walls for limiting the movement of the plunger.
19. In a mold, the combination with a 65 mold frame; of a mold box comprising opposite walls movably mounted in the frame; a plunger reciprocable between said walls, and means carried by the walls for limiting the movement of the plunger in both directions. 75
20. In a mold, the combination with a mold frame; of a mold box comprising opposite walls pivoted in the frame; a plunger reciprocable between said walls, a stop rod 80 having its ends mounted in the walls and traversing slots formed in the plunger, a stop bar carried on the plunger and crossing said rod, a bolt connected to the rod and traversing an aperture in the bar, and a nut 85 threaded on the free end of the bolt.
21. In a mold, the combination with a mold frame; of a mold box comprising opposite walls movably mounted in the frame; a plunger reciprocable between said walls, 90 and means carried by the walls and engaging parts on the plunger for limiting movement of the plunger in one direction and for adjustably limiting its movement in the opposite direction. 95
22. In a mold, the combination with a mold frame; of a mold box comprising opposite walls movably mounted in the frame; a plunger reciprocable between said walls, 100 and means carried by the walls for adjustably limiting movement of the plunger.
23. In a mold, the combination with laterally movable walls, of a plunger reciprocable between said walls and having outwardly exposed channels paralleling its direction of movement, and cores fixed on the walls and fitting said channels. 105
24. In a mold, the combination with a mold wall, of a plunger reciprocable along the face of said wall and having a channel 110 which opens against the wall and parallels the direction of movement of the plunger, and a core fixed on the wall and fitting said channel.
25. In a mold, the combination with a mold wall, of a plunger reciprocable along the face of said wall and having a channel 115 which opens against the wall and parallels the direction of movement of the plunger, and a core fixed on the wall and fitting said channel, said channel intersecting the molding face of the plunger and said fixed core projecting inwardly of the mold beyond said molding face. 120
26. In a mold, the combination with a mold frame, of walls pivoted along corresponding edges to said frame to form an expanding mold box, springs mounted in the frame and connected to the walls to move them normally to expanded position, and ro- 125
- 130

tatable wall closing elements interposed between the walls and said frame.

27. In a mold, the combination with a mold frame, of walls pivoted along corresponding edges to said frame to form an expanding mold box, springs mounted in the frame and connected to the walls to move them normally to expanded position, and rotatable wall closing elements interposed between the walls and said frame and positioned to hold the walls in closed position against the pressure of the springs.

28. In a mold, the combination with a mold frame, of an expanding mold box mounted therein and comprising a movable wall having a normal tendency to move to expanded position, a mold shaft journaled in said frame, a cam formed on said wall having a surface inclined with respect to the plane of the wall when closed and a surface paralleling that plane, and a stud extending radially of the shaft, said stud being positioned to traverse the inclined surface of the cam to close said wall upon oscillation of the shaft and to stand in perpendicular contact with said parallel cam surface when the wall is in closed position.

29. In a mold, the combination with a mold frame, of a mold box mounted therein and comprising an expanding mold wall having a core aperture and a normal bias toward expanded position, a mold shaft journaled in the frame, a core mounted for reciprocation in said aperture, and devices fixed upon said shaft whereby oscillation of the shaft in one direction closes the wall and shoots the core inwardly thereof and the reverse oscillation of the shaft withdraws the core and releases the wall.

40 30. In a mold, the combination with a mold frame, of a mold box mounted therein and comprising an expanding mold wall having a core aperture and a normal bias toward expanded position, a mold shaft journaled in the frame, a core mounted for reciprocation in said aperture, and devices fixed upon said shaft whereby oscillation of the shaft in one direction moves the wall to and holds it in closed position and shoots the core inwardly thereof and the reverse oscillation of the shaft withdraws the core and releases the wall.

31. In a mold, the combination with a mold frame, of a mold box mounted therein and comprising an expanding mold wall having a core aperture and a normal bias toward expanded position, a mold shaft journaled in the frame, a core mounted for reciprocation in said aperture, and devices fixed upon said shaft whereby oscillation of the shaft in one direction closes the wall and shoots the core inwardly thereof and the reverse oscillation of the shaft withdraws the core and releases the wall, said devices being proportioned to move the core

through a path longer than that of the adjacent portion of the wall.

32. A mold, comprising a mold frame, a movable mold wall mounted therein, a reciprocable core mounted in the wall, a mold shaft journaled in the frame, wall and core operating devices carried on the shaft, a shaft operating lever fulcrumed on an axis perpendicular to said wall when closed, and a shaft operating arm universally pivoted to said lever and pivoted to said shaft tangentially thereof.

33. A mold, comprising a mold frame, a mold wall carried therein and having spaced core apertures, a core bar positioned between said wall and the frame, cores fixed upon the bar and slidably engaging said apertures, and bar operating mechanism, said bar being reciprocable between the wall and frame and contacting with each to limit the movements of said cores.

34. A mold comprising a mold frame, a mold wall pivoted therein, and having spaced core apertures, a core bar positioned between said wall and the frame, cores fixed upon the bar and slidably and closely fitting said apertures, slide rods mounted in the frame and supporting said bar, and mechanism for reciprocating the bar and swinging said wall.

35. A mold comprising a mold frame, a mold wall pivoted therein, and having spaced core apertures, a core bar positioned between said wall and the frame, cores fixed upon the bar and slidably and closely fitting said apertures, slide rods mounted in the frame and supporting said bar, and mechanism for reciprocating the bar and swinging said wall, said mechanism being adapted to reciprocate the bar in a path constantly perpendicular to the wall and longer than the path of swing of the adjacent portion of the wall.

36. In a mold, the combination with a mold wall, of a plunger reciprocable along the inner face thereof and having a channel which opens against the wall, intersects the molding face of the plunger and parallels the direction of movement of the plunger, a core fixed on the wall, fitting said channel and projecting inwardly of the mold beyond said molding face, said wall having a transverse aperture flush with the inner extremity of the fixed core, and a sliding core mounted in the aperture and reciprocable across and in contact with said inner extremity of the fixed core.

37. In a mold, the combination with a mold wall, of a plunger reciprocable along the inner face thereof and having a channel which opens against the wall, intersects the molding face of the plunger and parallels the direction of movement of the plunger, a core fixed on the wall, fitting said channel and projecting inwardly of the

5 mold beyond said molding face, said wall having a transverse aperture flush with the inner extremity of the fixed core, and a sliding core mounted in the aperture and reciprocable across and in contact with said inner extremity of the fixed core, said sliding core being movable inwardly of the wall beyond the fixed core.

10 38. In a mold, the combination with a mold frame, and a palette board, of opposite walls pivoted in the frame and formed to overlap the ends and outer face of said board, and means interposed between each wall and the mold frame for resisting 15 swing of the walls outwardly of the board, said means being releasable and said walls having a normal tendency to recede from the board.

20 39. In a block press, the combination with a main frame, of a horizontal raceway supported therein, a carriage running on the raceway, a mold frame trunnioned in the carriage, and a mold carried by the mold frame.

25 40. A block press comprising, a main frame, a pressure supporting table positioned in the lower portion thereof, a press-

ing device in the frame spaced above and exerting pressure toward said table, an invertible, downwardly discharging, expanding mold carried in the frame for movement into and out of alinement with said table and device, and a movable mounting for the table whereby it is vertically reciprocated beneath the mold, said mounting comprising 30 a table frame one end of which is adapted to stand laterally of the main frame and on which the table is glidingly supported.

41. In a block press, the combination with a main frame, of a downwardly discharging mold trunnioned therein on a horizontal axis and shaped to form in horizontal position and discharge without movement from said position a block which is heavier on one side of the axis than on the other, and a constantly horizontal table 45 vertically reciprocable beneath the mold and movable into contact therewith whereby said block is discharged and carried from the mold in horizontal position. 50

In testimony whereof we have hereunto affixed our signatures.

WILLIAM C. BURRELL.
JOHN BELLINGHAM.
